UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

CUSHION-TOP CONSTRUCTION.

Application filed June 25, 1923. Serial No. 647,622.

This invention relates to improvements in cushion top construction for wardrobe trunks, and more particularly to the manner of securing the edge portions of the cushion to the trunk top.

In wardrobe trunks of the better class as now constructed, the trunk body is divided vertically medially into two sections which are hinged together and are adapted to swing horizontally to open position. One of these sections is usually provided with drawers and other compartments, and the other, called the wardrobe section, is usually provided with garment hanger tracks upon which garment hangers are slidably mounted. The tracks are usually of the extensible type to permit the hangers to be slid outwardly on the track while in suspended position. Garments are suspended by and folded over the hangers and in order to permit them to be freely removed from the trunk section, the upper end of the section is open and is provided with a cover which may be swung upwardly to open position. To maintain the garments and hangers in position, the top cover is provided with a cushion into which the hangers and apparel imbed when the cover is in closed position. As the cushion is of less size than the top cover, considerable work was required to form a finished edge for the cushion.

It is one of the objects of the present invention to provide a cushion top construction which presents a more finished appearance and which also acts as a means for sealing the joint between the top cover and the body portion of the trunk to form a dust tight joint.

A further object of the invention is to provide a cushion top which is of very simple construction, is strong and durable and is well adapted for the purpose described.

With the above and other objects in view, the invention consists of the improved cushion top construction and its parts and combinations as set forth in the claims, and all equivalents thereof.

In the accompanying drawing in which the same reference characters indicate the same parts in all of the views:

Fig. 1 is a front view of the upper portion of the wardrobe section of a wardrobe

trunk showing the top cover in open position and provided with the improved cushion top construction;

Fig. 2 is a transverse sectional view thereof taken on line 2—2 of Fig. 1;

Fig. 3 is a sectional view thereof taken on line 3—3 of Fig. 1; and

Fig. 4 is a sectional detail view of one side and top portion of the improved construction.

Referring to the drawing, the numeral 5 indicates the wardrobe section of a wardrobe trunk which has an open top and is provided with a top cover 9 hinged thereto. The top cover is formed with side flanges 9' positioned to overlap the upper edges of the rear and side portions of the wardrobe section. Garment hanger rails 10 and hinged extensions 10' are mounted in parallel relation in the trunk section and have garment hangers 11 slidably mounted thereon. The upper portions 11' of said hangers extend horizontally in straight lines to receive and support apparel draped thereover.

A cushion or pad member is mounted on the inner or bottom side of the top cover and comprises a base board member 12, a cushion or pad portion 13 and a top covering 14 preferably formed of a soft plush or other like soft material. The base member may be formed of any material that will maintain its shape and hold the pad in place and is adapted to be firmly connected to the top cover in any manner desired. A strip of thick felt or other soft material 15 is mounted on the inner face of the base member adjacent the rear and opposite side edge portions thereof, and forms a U-shaped pad or seal adapted to engage the upper edges 5' of the rear and opposite side edges of the wardrobe section 5 to provide a dust tight connection therebetween. The top covering 14, before mentioned, extends over the cushion and the felt, and between the cushion and the strip of felt it is cemented or otherwise fastened to the base member, as indicated by the numeral 16, to hold the cushion

and felt strip in place and space the felt from the cushion. The outer edge portions 14' of the top cover overlap the edge portions of the base board and are cemented or otherwise connected thereto as desired.

The inner front edge portion of the top cover is covered by a metal angle strip 17 forming the front edge of the top cover.

As thus constructed, the garment hangers 5 on the rails or garments draped on said hangers, will imbed into the cushion and be firmly held in position without wrinkling, and the upper edges of the wardrobe section will imbed into the pad, as shown in 10 Figs. 3 and 4.

From the foregoing description, it will be seen that the cushion top provides a hanger cushion of very simple construction which also possesses the function of sealing the 15 joint between the top cover and the wardrobe section.

What I claim as my invention is:—

1. A wardrobe trunk having a section provided with an upper end hinged cover, garment hanger rails mounted within the upper portion of the open end of said section, garment hangers slidably mounted on said rails, and a cushion member interposed between the cover and the rails and engaging the garment hangers and the upper edges of the trunk section, said cushion member being of greater thickness than the distance between the cover and the upper edges of the hangers and the trunk section upper edges to cause 25 said hanger and trunk edges to embed into the cushion member when the top cover is in closed position, said engagement between the trunk section upper edges and the cushion member forming a seal therebetween.

2. A wardrobe trunk having a section provided with an upper open end and a hinged cover, garment hanger rails mounted within the upper portion of the open end of said section, garment hangers slidably mounted on 40 said rails, and a cushion member mounted on the inner side of the cover and having a portion which engages the garment hangers and another portion which engages the upper edges of the said trunk section to seal the joint therebetween.

3. A wardrobe trunk having a section provided with an upper open end and a hinged cover, garment hanger rails mounted within the upper portion of the open end of said section, garment hangers slidably mounted on said rails, and a cushion member mounted on the inner side of the cover and having a medial portion which is on a lower plane than the other portion, said other portion of 50 higher plane extending around three edge portions of the lower plane portion for

forming a seal between the body of the trunk and the cover.

4. A wardrobe trunk having a section provided with an upper open end and a hinged 60 cover, garment hanger rails mounted within the upper portion of the open end of said section, garment hangers slidably mounted on said rails, and a cushion member mounted on the inner side of the cover and positioned to cause the garment hangers to imbed therein when the cover is in closed position, said cushion member also having a yielding part adjacent the side and rear edges of the cover and spaced from the hanger cushion portion which engages and is imbedded into by the upper edges of said trunk section to 70 form a dust tight seal therebetween.

5. A wardrobe trunk having a section provided with an upper open end and a hinged 75 cover, garment hanger rails mounted within the upper portion of the open end of said section, garment hangers slidably mounted on said rails, a cushion member mounted on the inner side of the cover and positioned to cause the garment hangers to imbed therein when the cover is in closed position, said cushion member also having a yielding part adjacent the side and rear edges of the cover and spaced from the hanger cushion portion 80 which engages and is imbedded into by the upper edges of said trunk section to form a dust tight seal therebetween, and a covering material extending over the hanger cushion portion and the edge cushion portion, portions of said material between the cushion and the yielding part being connected to the cover.

6. A wardrobe trunk having a section provided with an upper open end and a hinged 95 cover, garment hanger rails mounted within the upper portion of the open end of said section, garment hangers slidably mounted on said rails, a base member mounted on the inner side of the cover, a cushion carried by 100 a medial portion of the base member, a U-shaped pad member mounted on the base member adjacent edges of the base member and spaced from the cushion, a covering material extending over the cushion and the 105 U-shaped pad member and connected to the base member between the cushion and the pad member and to the outer edge portions of the base member, and a strip covering one edge portion of the covering material.

In testimony whereof, I affix my signature.
JULIUS RITTER, JR.
